UNITED STATES PATENT OFFICE

CLAUDE LOCREILLE, OF FANQUEZ, BELGIUM

APPARATUS FOR ROLLING GLASS

Application filed March 31, 1930, Serial No. 440,551, and in Belgium April 6, 1929.

The present invention relates to the rolling of glass by means of rolling trains comprising pairs of rolls between which molten glass is pressed and drawn into plates or sheets. In such glass rolling plants the rolled sheet is usually delivered on a movable receiving table which carries it to, or into, an annealing furnace, the motion of the table being as much as possible synchronized with that of the rolls in order to avoid that too quick or too slow a movement of the table might result in unduly stretching or compacting the sheet between the table and the feeding rolls. It is however difficult to obtain perfect synchronism more particularly when the sheet of glass is being printed while it is rolled, and the sheets often undergo deformations which result in wasting a not inconsiderable percentage of the goods produced.

In order to remedy this inconvenience, in accordance with this invention, instead of moving the receiving table with respect to the rolling train, I cause the rolling train to move towards the table which is made stationary, the rolling train delivering the sheet onto the table as it progresses, such progression being easily synchronized with the delivery, for example by using the same motor for driving both the rolls and the rolling train as a whole. Preferably the frame of the rolling train is slidably mounted on the base of the stationary receiving table, and it may be driven by pinions and racks, or by nuts and screws, the racks or the screws being arranged along the sides of the table while the pinions or the nuts are carried by the side plates of the rolling train and are driven from a motor which is mounted on the slideable frame and also drives the rolls for rolling the glass.

The stationary receiving table may advantageously be located in front of the entrance of the annealing furnace, the rolling train being moved at right angles to said furnace and carrying along with it a long and narrow guard or plate which bridges the gap between the table and the entrance of the furnace, so that the glass sheet may be slid from the table into the furnace without catching in the gap.

In the accompanying drawings diagrammatically illustrating by way of example various embodiments of my invention:

Fig. 1 is a sectional side elevation of a plant with a movable rolling train with rack and pinion drive,

Fig. 2 being an end elevation and

Fig. 3 a plan view of same.

Fig. 4 is a sectional side elevation showing another form of rolling train.

Fig. 5 is a similar view of a rolling train with nut and screw drive.

In all the figures of the drawing *a* is the rolling train, *b* the receiving table and *c* the entrance of the annealing furnace in front of which the table *b* is permanently mounted. The side plates *d* of the rolling train *a* on each side of the table *b* rest on the base *e* of the latter, which base is provided with suitable guideways in which the rolling train *f* slides as it delivers the rolled sheet of glass onto the table.

In Figs. 1 to 4 the movement of the rolling train is produced by means of pinions *h* mounted on the inside of the plates *d*, said pinions meshing with racks *i* parallel to the sides of the table *b* and secured to the base *e*. A motor *k* on an outer bracket secured to a plate *d* drives both the rolls *l, m* of the rolling train and the pinion *h* by means of suitable gears such as shown at *n* in Fig. 2.

The gear ratios are so chosen that the speed of translation of the rolling train shall correspond with the rate of delivery of the glass so that the glass sheet shall neither be stretched nor compacted when it is deposited on the table by the travelling rolling train.

In Fig. 5 the pinions *h* and racks *i* are replaced by rotatable nuts *o* mounted on the side plates *d* and threaded rods *p* secured on both sides of the table *b*. The nuts *o* are locked against axial motion by their bearings, and as they are rotated by the motor *q* they are screwed on the rods *p* and carry the rolling train forward or backward, as they turn in one or in the other direction. As shown the nuts *o* may be provided on their periphery with helical teeth engaged by a worm *r* driven by the motor *q*.

In Figs. 1 and 5 the glass sheet *f* is directly deposited from the rolling train onto the table. In Fig. 4, it is first turned around roll *m*¹ before coming to rest on the table, as described in my co-pending patent application Serial No. 439,516.

Whatever be the construction adopted, the rolling train *a* is provided with a narrow plate or guard *t* trailing after it, which guard fits in the gap between the entrance of the furnace *c* and the table *b*, so that as the rolling train moves along, the guard *t* closes said gap and covers the rack *i* or the threaded rod *p* on the base *e*. The guard *t* is secured to the side plate *d* nearest the furnace *c* and it may be supported by suitable guides. When the glass sheet has reached a position in front of the furnace *c*, the guard *t* forms a bridge over which the sheet may be slid 20 from the table *b* into the furnace.

Of course the constructional details herein described and illustrated may be varied without departing from the scope of my invention as defined by the appended claims.

25 I claim:

1. In a glass rolling plant, the combination with a glass annealing furnace, of a stationary table in front of said furnace, said table being separated from said furnace by a gap, 30 a base for said table, a travelling rolling train movable on said base, and means for bridging said gap, said bridging means being carried by said rolling train.

2. In a glass rolling plant, the combination with a glass annealing furnace, of a stationary table in front of said furnace, said table being separated from said furnace by a gap, guideways on each side of said table, a 40 rolling train movable in said guideways, driving means on said rolling train for moving same towards and away from said furnace, and means on said rolling train for bridging said gap.

3. In a glass rolling plant, the combination with a glass annealing furnace, of a table in front of said furnace extending at right angles thereto, said table being separated from said furnace by a gap, guideways 50 on each side of said table, a rolling train movable in said guideways, means for moving said rolling train along said guideways, and a guard on said rolling train for closing said gap.

4. In a glass rolling plant, the combination with a glass annealing furnace, of a table in front of said furnace extending at right angles thereto, a base for said table, said base being of greater width than said 60 table, there being a gap between said table and said furnace, a rolling train movable on said base, means for moving said rolling train along said table, and means on said rolling train for closing said gap.

65 5. In a glass rolling plant, the combination with a glass annealing furnace, of a

table in front of said furnace, said table being separated from said furnace by a gap, a base for said table, a rolling train movable on said base, said rolling train comprising a frame resting on said base on either side of said table, rolls mounted in said frame, a motor carried by said frame, a driving connection between said motor and said rolls, means for moving said frame along said table, a driving connection between said motor and said means, and a guard rigidly connected to said frame for closing said gap.

6. In a glass rolling plant, the combination with a glass annealing furnace, of a table in front of said furnace extending at right angles thereto, a base for said table, said base being of greater width than said table, there being a gap between said table and said furnace, a rolling train movable on said base, said rolling train comprising a frame resting on said base on either side of said table, rolls mounted in said frame, a motor carried by said frame, a driving connection between said motor and said rolls, means for moving said frame along said table, a driving connection between said motor and said means, and a guard for closing said gap, said guard being secured to said frame.

In testimony whereof I affix my signature. 95
CLAUDE LOCREILLE.
